UNITED STATES PATENT OFFICE.

HUBERT F. KRANTZ, OF BROOKLYN, NEW YORK, ASSIGNOR TO KRANTZ MANUFACTURING COMPANY, INC., OF BROOKLYN, NEW YORK, A CORPORATION OF NEW YORK.

AUTOMATIC MOTOR-STARTER.

1,267,324.

Specification of Letters Patent. Patented May 21, 1918.

Application filed February 18, 1916. Serial No. 79,098.

To all whom it may concern:

Be it known that I, HUBERT F. KRANTZ, a citizen of the United States, and residing at Brooklyn, in the county of Kings and State 5 of New York, have invented a new and Improved Automatic Motor-Start, of which the following specification is a full disclosure.

This invention proposes a semi-automatic 10 motor starting switch devised to compel the first inrush of current due to the initial low back electro-motive-force of the motor to be drawn directly from the mains independently of the motor fuses and thus avoid the 15 blowing of said fuses during the initial starting period of the motor.

To provide an automatic device governing 20 the lapse of time before the current is taken through the motor fuses, is one of the primary objects of this invention; and to 25 devise a simple and rugged mechanism for doing so is the chief aim of the illustrated embodiment thereof.

Another purpose is to create a semi-automatic 30 means whereby the hand is enabled unrestrictedly to throw the switch into its motor starting position; and in which the subsequent act of connecting the fully started motor with the mains through the fuses 35 will be performed automatically and without requiring any personal attention on the part of the user.

Other objects will be in part obvious from 40 the annexed drawings and in part indicated in connection therewith by the following analysis of this invention.

This invention accordingly consists in the 45 features of construction, combinations of parts, and in the unique relations of the members and in the relative proportioning and disposition thereof; all as more completely outlined herein.

To enable others skilled in the art so fully 50 to comprehend the underlying features thereof that they may embody the same by the numerous modifications in structure and relation contemplated by this invention, drawings depicting a preferred form have been annexed as a part of this disclosure, 55 and in such drawings, like characters of reference denote corresponding parts throughout all the views of which:—

Figure 1 is a plan of the automatic switch mechanism. Fig. 2 shows the switch ele-

ments as arranged in their normal running 55 position. Fig. 3 shows more specially the means for automatically producing the operation of the parts.

Referring to the drawings, 1 indicates a base plate of insulating material on which 60 is mounted one or more bus-bars 2. As several bus-bars and switches are shown which are of identical construction, it will suffice to describe but one. Overlying these bus-bars is a rocking blade holder formed of parallel 65 strips 3 and 4 having their ends secured at the one end to a gudgeon providing the pivot 5 which is mounted in a side plate 6 uprising from the base board 1. At the opposite end, the strips 3 and 4 are secured to a part 7 70 providing arms 8 for actuating the same and providing also a shaft 9 which is journaled in the plate 10. A spring 11 tends constantly to urge the brush-holder, formed of the plates 3 and 4, in an anti-clock-wise 75 direction, as shown by the drawings. Mounted on the brush-holder and insulated therefrom by means of the plates 12 are a number of brushes 13, preferably of resilient construction, as shown, although a knife-blade 80 arrangement is equally applicable. When the brush-holder is in the position shown by Fig. 2 with the blades contacting with the bus-bars, the position is normally retained by means of a toggle formed of the 85 links 14 and 15, the latter being pivoted about the fixed pivot 16 and the former being pivoted to the pin 17 mounted on the arm 8. A floating pivot 18 connects these links and they are prevented from moving 90 out of the dead center position shown by Fig. 2 by an abutment against the pin 19.

In this embodiment, the switch just described is that ordinarily employed during the normal running of the motor, but in addition to that switch this invention proposes an auxiliary switch S which is used merely during the initial starting period of the motor when a great inrush of current is consumed owing to the momentary low reactance of the motor.

This auxiliary switch may be mounted and constructed in precisely the same manner as that previously described and therefore these details need not be further elaborated. 105 It is to be noted that the location of the switch S with relation to the switch 13 is of no consequence providing, however, that

it derives current independently of the fuse plugs intervening between the switch 13 and the main line.

A very important characteristic of this invention lies, furthermore, in the mechanism whereby the switch S may be used temporarily for starting purposes and the switch 13 for normal running purposes; the functioning being such that when the motor is 10 to be started the switch S will be caused to establish contact with the main line either simultaneously or slightly before the switch 13 and within a few moments thereafter the switch S will be disconnected while leaving the switch 13 in operation.

One very simple instrumentality for achieving this result is shown in the drawings, and it consists of a connection between the device controlling the switch 13 and the 20 device controlling the switch S such that the latter device will be positively operated either immediately before or simultaneously with the other device so as to throw the switch S into its closed circuit position not 25 appreciably later than the switch 13 is caused to assume the same position. This mechanism also embodies means effective during subsequent movement thereof to snap open switch S, and it also embodies 30 means enabled to go into action during a still later movement of the mechanism to snap open the switch 13 to effect the stoppage of the motor. All of this may be accomplished by a very simple arrangement 35 which here merely assumes the form of a lost motion link together with a link actuator.

This lost motion link is indicated by L and it is provided with an opening 21 and 40 engages the pivot 22 of the toggle controlling switch S, whereby this toggle may be either "erected" or "broken" by a shifting of the link L. The other end of the link L is an elongated slot 23 which provides lost 45 motion and enables two different contact surfaces to come into action at different times with relation to the floating pivot 22. That is to say, it provides a contact surface 24 which becomes effective on the floating pivot 50 18 at substantially the same time that the opening 21 becomes effective on the floating pivot 22, when the link L is moved in the direction causing the switch blades to make contact with the bus-bars.

55 On the other hand, the contact surface 25 bears such a relation to the opening 21 that it will not become effective against the floating pivot 18 until the opening 21 has already broken the other toggle by shifting 60 the floating pivot 22. Upon a continued motion of the lever L, the contact surface 23 will become effective against the pivot 18 so as to break the toggle thereof and open the switch 13. It is to be noted that the 65 opening 21 provides a certain amount of

lost motion with respect to the floating pivot 22 so that when the latter has reached its final position, the link L may still move sufficiently farther to break the toggle of the blade 13; the lost motion of the slot 23 being considerably greater than that of the opening 21 since the latter need only be sufficient to enable the link L to throw the floating pivot 18 across its dead center, whereas the lost motion in the slot 23 must be sufficient to accommodate the full swing of the floating pivot 18.

The terminal leading to the motor is indicated by 25' and is connected independently of a fuse with the terminal or contact 26 with which the switch S establishes connection; whereas the terminal 25' is connected with the other contact 27 of the switch 13 only through an intermediary in the nature of a fuse P. A convenient manner of doing this consists in providing a block M of insulating material and arranging a U-shaped strip N on one end of it and another U-shaped strip O on the other end of it and providing the ends of these 90 strips or conductors with spring-clips 31 and 30 suitably formed to receive the ends of the fuse P.

For the purpose of operating the switch blades by means of the link L, a manually 95 or automatically actuated element may be employed. Reduced to its simplest terms, this element may comprise a lever R pivoted at 32 to the side plate 10 and having a pin 33 entering a lost motion aperture 34 in 100 the link L. This lost motion permits the springs to effect a quick break of the switch blades without overcoming the inertia of the lever R. This lever preferably embodies a 105 detent mechanism for holding it in its "running" position and to that end a small spring-pressed pawl 35 is adapted to enter a suitable recess 36 in the edge of the plate 10 and hold the starting lever in place. A pressure of the hand will, however, suffice 110 to cause the pawl to override this recess.

This invention furthermore proposes an automatic instrumentality for actuating the lever R when it has been released by the hand. This mechanism is of such a nature 115 that while shifting the switch from the motor starting to the normal running position, sufficient time is consumed to enable the motor to develop its full running speed and thereby create sufficient back electro-motive-force so that no great inrush of current will be drawn from the mains.

This mechanism is of such a variety that when the hand lever is thrown into the motor starting position, it will set the 125 mechanism so that it may subsequently function to partially throw the hand lever; and preferably the connection will be such that the hand supplies the instrumentality with the power necessary for this purpose, 130

as by lifting a weight or winding a spring. Of course, this instrumentality may assume various forms, but one of the many embodying my invention and well suited for 5 the purpose, is illustrated specifically by Figs. 1 and 3 and is constructed as follows:

An actuator A in the form of a segment of a gear wheel is pivoted to swing about a suitable center, as for instance a stud 32 10 which also pivots the hand lever R, and this actuator A has an abutment *a* adapted to bear against a contact surface or shoulder *c* provided by the lever R so that when the lever is lifted, it may cause the actuator A 15 to swing anti-clockwise; and likewise, the actuator A may thereupon return the lever R to its intermediate or normal running position. A stop *b* is arranged so that the actuator A will not urge the hand lever R 20 beyond its intermediate or normal running position and so that the detent 35 may retain it yieldably in that position. When the hand lever R is lifted and the actuator A swung upwardly, power is stored in a propelling mechanism as by causing a weight D 25 to be lifted by a drum B through the cord *r*; this drum being pivoted about the stud *e* and turned clockwise by the engagement of its teeth *f* with the teeth *d* of the actuator 30 A. It is not intended, however, that this stored up power shall be immediately effective to at once throw the actuator A into its normal position, and a suitable retarding device is therefore arranged to coöperate 35 with the drum B. This timer may advantageously be in the form of an escapement comprising an escape wheel *h* and a detent device through which periodical manipulations are imparted to a pendulum E to keep 40 it in oscillation, and through which, in turn, motion is imparted or permitted by the return movement of the pendulum. This escapement may consist of a rock block C from which the pendulum E is suspended by 45 means of the pendulum rod *p*. This rock block C carries two arms *m* and *n* providing pivots *k* and *o* respectively upon which are swung the weighted or gravity-acting pawls *z* and *x*. These pawls engage the teeth *h* 50 whenever they are permitted to do so by the pins *y* and *w*. These pins are contained within openings in the pawls *z* and *x* which provide sufficient back-lash so that during the power storing movement of the actuator 55 A, the teeth *h*, will be enabled freely to swing past these pawls ratchetwise. On the other hand, under the impulse of the teeth *h*, the pawls *z* and *w* are successively pressed to one side and slipped past the teeth, 60 thereby maintaining the pendulum E in a state of oscillation. This results in a steady and deliberate return of the actuator A which is the sort of motion required for returning the switch handle R, to its normal 65 position.

It is to be noted that the above-described automatic instrumentality need not be connected with the hand lever R so as to be moved thereby when the latter is being brought to its off position. Even so, it will 70 not be possible to start the motor by moving the hand lever R directly into and leaving it in its intermediate position, because the mechanism is of such a nature that the hand lever R is ineffective to throw the normal running switch 13 into its closed circuit position appreciably before the temporary starting switch S has also been thrown into its closed position.

This peculiarity is inherent in the nature 80 of the toggle and lost motion operating parts. In other words, when both of the toggles are broken, the hand lever R may be brought to its intermediate position without actuating either switch by reason of the lost 85 motion in that direction. This is an important feature because it safeguards the entire organization from accidental or ignorant manipulation on the part of the user.

As many changes could be made in this 90 construction without departing from the scope of the invention as defined in the following claims, it is intended that all matter contained in the above description or shown in the accompanying drawings, shall 95 be interpreted as illustrative only and not in a limiting sense.

Having thus revealed this invention, I claim as new and desire to secure the following combinations of elements, or equivalents thereof, by Letters Patent of the 100 United States:—

1. A switch mechanism combining a first and a second switch blade; means for individually holding said switches in "on" position simultaneously; automatic time controlled means for rendering ineffective the means for retaining said first switch in "on" position; and manually operable means for rendering ineffective the means for holding 105 the two second switch "on."

2. A switch mechanism combining a first and a second switch; automatic means acting through a pre-determined time interval for drawing said first switch; and manually 110 operable means for throwing said second switch.

3. A mechanism of the nature disclosed combining a hand lever adapted to be moved through a pre-determined arc two switches 115 connected to be moved into "on" position by full movement of said lever; a member movable by said lever throughout a portion only of the arc of said lever; and means for automatically enabling said member to resume its normal position and to partially return the lever to thereby move one of the switches to "off" position.

4. An instrumentality of the nature disclosed combining a member manually oper- 130

- able through a predetermined stroke; an element adapted to be displaced by said member during the latter part only of its stroke; two switches connected to be moved 5 into "on" position by full movement of said member, and means for compelling said element to resume its original position and to thereby return one of the switches to "off" position.
- 10 5. A first and a second switch; a member operable manually to throw the second switch; an element for throwing the first switch, said element being arranged to be moved by said member during the latter 15 part of the stroke of said member; and mechanism for causing said element automatically to resume its original position at a retarded rate to thereby return said first switch to "off" position.
- 15 6. A switch mechanism combining a first switch and a second switch; means operable manually to throw both of said switches "on;" and time controlled means operable automatically thereafter to throw one only 20 of said switches "off."
- 20 7. A switch mechanism combining a first and a second switch; means operable manually to throw both of said switches "on;" a device operable automatically after a pre- 25 determined time interval to throw said first switch "off;" and means whereby the mentioned manually operable means may be employed to throw the second switch "off."
- 25 8. A switch mechanism combining a first switch; a member operable manually both 30 to open and close the same; a second switch; an element movable by said member to close said second switch; and time controlled means for opening the second switch.
- 30 9. A motor starting switch mechanism 40 comprising a conductor, a fuse, a switch by means of which running current may be derived from the conductor for passage through the fuse to the motor; a shunt from the conductor around the fuse by 45 means of which starting current may be derived from the conductor for the motor without traversing the fuse, said shunt including a separate switch, a single operating element for said two switches connected 50 to move said two switches simultaneously into "on" position, and the connections between said operating element and the shunt switch comprising a time controlled device adapted to automatically move the shunt 55 switch into "off" position while the first mentioned switch stands in "on" position.
- 35 10. A switch mechanism combining a first and a second switch, manually operable means for operating the second switch, and means operable automatically independently of said manually operable means for operating the first switch.

In witness whereof I hereunto subscribe my name, as attested by the two subscribing 65 witnesses.

HUBERT F. KRANTZ.
